United States Patent Office.

TIMOTHY EARLE, OF SMITHFIELD, RHODE ISLAND.

Letters Patent No. 105,057, dated July 5, 1870.

IMPROVED EGG-BEATER.

The Schedules referred to in these Letters Patent and making part of the same.

To all whom it may concern :

Be it known that I, TIMOTHY EARLE, of the town of Smithfield, county of Providence and State of Rhode Island, have invented a certain new and useful Egg-Beater.

My invention relates to the novel construction and arrangement of the several parts composing the beater; and I do hereby declare that the following specification, taken in connection with the drawing furnished and forming a part of the same, is a true, clear, and exact description thereof.

The drawing represents, in perspective, one of my improved egg-beaters, complete.

A is the handle.

B is a bevel driving or crank-gear attached to the handle.

C and C' are suspension rods, attached, at their upper ends, to the lower end of the handle A. They are composed of a continuous piece of wire, and, when in position, they are slightly nearer to each other at their tops than at their lower ends.

D and E are revolving beaters, mounted side by side upon the rods C and C'. They are each made of a flexible strip of sheet metal, in an elongated oval form, and are provided at their tops with gear-wheels, to which they are attached.

F is a pinion-gear, mounted on a stud projecting downward from the handle A. This gear has a line of straight teeth, which mesh into the gears of the beaters D and E, and a line of beveled teeth to gear with the teeth of driving-gear B.

Upon turning the driving or crank-gear, the two beaters are revolved rapidly in one general direction. At the nearest point of connection between the two, the cutting-edges of the beaters pass each other in opposite directions.

The novelty of my arrangement lies in the peculiar construction, by means of which it occupies less space and is more economical in construction than other beaters of the general character.

I do not broadly claim the double beaters, as they have been used before.

I do claim—

The beaters D and E, mounted upon suspension rods C and C', operated by the driving-gear B and pinion F, when all are constructed and arranged to operate as set forth.

TIMOTHY EARLE.
